[57] CLAIM

The ornamental design for ceiling fan support or similar article, as shown and described.

DESCRIPTION

FIG. 1 is a perspective view of ceiling fan support or similar article showing my new design;

FIG. 2 is a rear elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a left side elevational view thereof; and

FIG. 8 is a reduced perspective view thereof, with the broken-line showing of the ceiling-mounted holders and fan being for illustrative purposes only and forming no part of the claimed design.
